MECHANIC'S SHOP WORK LAYOUT TOOL OF
THE HEAD AND PIVOTED BLADE TYPE

Julius C. Thursack, Buffalo, N. Y.

Application March 21, 1950, Serial No. 150,896

9 Claims. (Cl. 33—100)

1

This invention relates to a mechanic's lay-out tool for shop work, proposing a tool of the general type which combines a blade and head, the blade being pivotally connected to the head for the purpose of sundry angular adjustments.

The object of the invention is to provide a self-contained tool of the above general type having novel features of structure and relation which enable the selection of various phases of cooperative capacity of the head and blade, phases within substantially the full range of items of shop layout work. Thus the improved tool, in and of itself and without requiring any association of special and structurally independent devices, is capable, for shop lay-out purposes, of an extremely wide range of uses, among which may be mentioned, as examples and not in a limiting sense, its uses as a square having a reversible capacity, a bevel, a reversible protractor of extreme range, as a tool for locating within a wide range of diametrical dimensions the center lines or diameters, either inside or outside, of objects of circular outline, e. g. patterns of various kinds, and the axial centers of such objects, and as a tool for applying squaring lines or angle lines to either inside or outside annular faces of sundry objects. A tool in accordance with the invention is capable of various other uses which will be readily apprehended by the skilled mechanic and is of special value in such fields as wood and metal pattern making and tool and die making.

Generally speaking the tool of the invention is characterized by a transverse head having along one edge face a centering feature and bearing a protractor scale, by the provision of sundry openings adjacent the edge face of the head which has the centering feature, by the provision of a row of openings concentric to the protractor scale, by the provision of pins for selective fitting in various of the openings and for projection at either side of the head, and by the provision on the blade of features for cooperation with the pins, according to their particular arrangement and for various purposes of utility.

In the drawings:

Figure 1 is a top plan view showing the tool with its head and blade in such relation as to provide a square generally similar to a T square, the parts in this relation being available for sundry purposes of use and the blade being located above the head.

Figure 2 is a view in top plan showing the tool in reverse relation to the position in which it is shown in Figure 1, that is to say, turned in a lateral direction upside down from the position

2

in which it is shown in Figure 1 and with the blade located below the head.

Figure 3 is an end elevation as viewed from the rear edge face of the head with the parts in the relation shown in Figure 1.

Figure 4 is a detail fragmentary sectional view on the line 4—4 of Figure 1.

Figure 5 is a detail fragmentary sectional view of one of the pins as fitted in an opening extending between the upper and lower faces of the head, this view being taken, for example, on the line 5—5 of Figure 1.

Figure 6 is a view similar to Figure 1 but showing the tool as used for the location of center lines or diameters of objects of circular outline within a range which can be accommodated by the centering feature provided on an edge face of the head.

Figure 7 is a partial top plan view showing the tool with its blade located above the head and positioned 180° distant from the location in which it is shown in Figure 1 and also showing the tool as in use for locating the diameter of an internally presented annular surface.

Figure 8 is a view in partial plan in a position inverted from the position of use and with its parts in a relation for use corresponding to their relation as shown in Figure 2 whereby, the tool being related to the work in the manner generally shown in Figure 2, extremely "flat" angular plotting lines may be drawn.

Figure 9 is a perspective view showing the tool as in use for the application of angle lines to an internally presented annular surface of an object.

Figure 10 is a perspective view showing the tool as in use for the application of angle lines to an externally presented annular surface.

The primary elements of the tool are a flat-faced head 1 and a blade 2. The head has an edge face 3 which has straight alining portions 3a providing a functional straightedge, and is formed between its ends, and preferably at a central location, with a somewhat shallow or wide angled V-shaped recess 4 whereby, for certain

purposes of use, the head may serve as a center head, the straight alining portions 3a extending for a substantial distance beyond each end of the recess 4. The blade 2 is connected to the head by a pivot pin 5, the axis of which is coincident with a line bisecting the angle of the recess 4. The pin 5 is provided at one end with an integral head 6 and the head 1 is formed in each of its opposite flat faces, distinguished as A and B, with a recess 7, either of which recesses may accommodate the head 6 in a flush relationship to the

adjacent flat face of the head 1. The part of the pin 5 which projects beyond the head 1 is threaded as at 8. The blade 2 is provided with a coplanar apertured lug 9 which projects from the fiducial edge 10 and the pin 5 projects through the aperture of the lug 9, having a fit in such aperture sufficiently close to prevent loose play. The threaded part of the pin 5 carries a wing nut 11 by means of which the blade 2 may be clamped to the head and thereby fixed in any angular position to which it may be moved, the nut 11 preferably bearing directly against a washer 12 interposed between it and the blade 2. The axis of the pin 5 is in alinement with the fiducial edge 10 of the blade 2. The blade 2 may be selectively positioned adjacent either flat face of the head 1, the drawings in Figures 1, 6 and 8 showing the blade adjacent the face A.

For the use of the tool as a protractor the head 1 carries upon one of its faces, e. g. the face A, a protractor scale 13 of semicircular extent with its radial center coincident with the axis of the stem 5, the terminals of the scale 13 being coincident with a base line 14 which, of course, is parallel to the straightedge 3. The blade 2 has a straight alining extension 2a beyond the lug 9 and in the use of the protractor scale 13 the extension 2a projects across the scale with its edge 10a extending radially with respect to the scale and in alinement with the fiducial edge 10 of the blade.

In accordance with the invention the head 1 is provided with openings 15, in different series, between its faces A and B, each of which openings is available for the accommodation of an unheaded rod-like pin 16 of uniform diameter. In any active setting of a pin 16 it will project well beyond one of the flat faces A or B of the head 1 and its inner end face will be substantially flush with the opposite flat face of the head 1. Thus, as shown in Figure 5, a pin 16 is shown as projecting upwardly beyond the face A of the head 1 with its lower end face substantially flush with the other face B. The openings 15 are of uniform diameter and each pin 16 is of a diameter conformable to the openings whereby it may have a close friction fit in any opening such that it will be stably positioned and may be shifted by thumb pressure to project beyond either of the faces A or B of the head.

In accordance with the invention the openings 15 are provided in functionally differentiated series. Thus one series C is in a row adjacent, and parallel to, the straightedge 3 and a second series D is concentric with the scale 13 and preferably adjacent its perimeter. A third series E, comprising but two openings, is optionally, and preferably, provided, each opening being located adjacent an opening at the outer end of the series C and the two openings of the series E being alined in parallel relation to the openings of the series C and being located between the two series C and D.

The number of openings in the series C and D is, in each instance, a matter of selection. Generally speaking, six openings in the series C and five openings in the series D will be ample. The openings of the series C are provided in equal number at each side of, and symmetrical to, the apex of the recess 4 and at each side of the apex are in suitable spaced relation. Thus the openings of series C are a pair, each adjacent the apex, a pair, each at an end of the series and a pair intermediately located, the

openings of corresponding pairs being equidistant from the apex. The axis of the central opening of the series D is coincident with a radial line which bisects the angle of the recess 4. The other openings of the series D are arranged symmetrically to the central opening, two at each side. The openings of the series D are preferably equidistantly spaced.

In the embodiment disclosed the tool may be normally equipped with five similar pins 16, two of which, for most purposes, may be normally arranged in openings of the series C in symmetrical relation to the apex of the recess 4 and the other three of which may be normally arranged in the openings of the series D, one in the central opening and the other two in adjacent openings. Each pin 16, as above noted, has a close friction fit in any one of the openings 15 and may be shifted by finger pressure to project beyond either face A or B of the head 1, as shown, for example, in Figure 5, an end face of a pin 16 as projected beyond either face A or B of the head 1 being flush with the opposite face. It will, of course, be understood that the mechanic, in his use of the tool, may have a supply of similar pins 16 in the event that, because of loss or special circumstances, a pin or pins in addition to the five pins above referred to should be needed.

For the purpose of direct cooperation with some determined one of the pins 16 and resultant cooperation with the head 1, the blade 2 is formed in the edge 10a of its extension portion 2a and near the end thereof with a recess 17 distant, by the extent of the radius of an arc of the scale 13, preferably the outer arc, from the axis of the pin 5; in its body portion the blade 2 is formed with a clearance opening 18, distant from the axis of the pin 5 by the same extent as the recess 17; and beyond the opening 18 the blade 2 is formed with a slot 19, the ends of which provide shoulders 20 for cooperation with a pin 16.

By virtue of the features of structure and combination above described the tool is available for the various purposes of use, some of which are shown, by way of example, in the drawings and also for other purposes which the skilled mechanic will appreciate and illustration and description of which is deemed unnecessary.

Figure 1 shows the use of the tool as a T square with the straightedge 3 bearing against a straight side of a flat rectangular work piece P. In this use the two pins 16 in the openings of the series C have been positioned to project beyond the face B of the head 1, their inner ends being flush with the face A, and the pin 16 which is located in the central opening of the series D has been positioned to project beyond the face A, the other two pins in the openings of the series D being positioned to project beyond the face B with their inner ends flush with the face A; the blade 2 has been swung from a position at the right of the position in which it is shown in Figure 1 to the position shown wherein the pin in the central opening of the series D serves as a stop and is accommodated in the recess 17; and the wing nut 11 has been tightened firmly to secure or clamp the blade 2 in the position shown wherein it extends at a right angle to the straightedge 3 and its fiducial edge 10 bisects the angle formed by the sides of the recess 4.

The tool as shown in Figure 1, with its straightedge 3 bearing against the straight side of the

piece P, may also be used as a protractor. In such use the pin 16 in the central opening of the series D is positioned to project beyond the face B with its inner end substantially flush with the face A as shown by dot and dash lines in Figure 5. Thus, when the tool, positioned in relation to the work piece P as shown in Figure 1 is to be used as a protractor all of the pins 16 are positioned to project beyond the face B of the head 1 and their inner ends are substantially flush with the face A and the wing nut 11 is backed off sufficiently to permit the manual movement of the blade 2 about the pivot pin 5. In the use of the tool as a protractor the plotting lines are marked in either or both directions on the work piece P, these lines being sufficiently exemplified at P' in Figure 1.

With the parts of the tool in the relation shown in Figure 1 for use as a T square, as above described, the tool may also be applied to the circumferential faces of objects for the determination or location of diameters. This use of the tool is illustrated in Figures 2 and 6. Figure 6 assumes objects of diameters which may be accommodated between the angular faces of the recess 4 and shows, in dot and dash line, objects S and S' at the extreme limits of such accommodation. Figure 2 assumes similar objects having diameters exceeding the capacity of the recess 4 and shows in dot and dash lines two objects T and T' at the extreme limits of such accommodation.

In the use of the tool as shown in Figure 6 the head 1, by virtue of the recess 4, serves as a center head. Likewise with the tool positioned in relation to either of the work pieces S or S' the tool may be used for locating axial centers or as a protractor, the pins 16 and the wing nut 11 being in the relations above described for the use of the tool as a protractor in the position shown in Figure 1. In this use of the tool the blade 2 adjoins and extends across a flat end face of the work piece.

In the use of the tool as shown in Figure 2 the head 1 also serves as a center head but does so by virtue of a pair of pins 16 in openings of the series C and the blade 2, as in the example shown in Figure 6, adjoins and extends across a flat end face of the work piece. Since the pins 16 which enable this particular use of the tool as a center head are adjacent the straightedge 3 and the objects T or T' exceed the capacity of the angle defined by the sides of the recess 4, the tool is reversed but with its straightedge 3 adjacent the work piece, that is to say, with its face B at the upper side and its face A at the lower side. In such reversal the two pins in the openings of the series C are shifted to positions wherein they extend beyond the face A, at that time the lower face. The pin in the central opening of the series D is also positioned to extend beyond the lower face A in order to serve as a stop in relation to the blade extension 2a as above described in connection with the use of the tool as shown in Figure 1. If the use of the tool as shown in Figure 2 be limited to the location of a diameter the position of the pins in the openings of the series D at each side of the central pin is immaterial. With the parts in the relation shown in Figure 2 the tool may also be used as a protractor in which case the nut 11 is backed off to an extent suitable to permit the facile movement of the blade 2 about the pivot pin 5 and all of the pins in the openings of the series D are positioned to project above the then upper

face B with their inner ends substantially flush with the face A.

Figure 7 shows the use of the tool in connection with a piece U (shown in dot and dash lines) having an internally presented annular surface U', the tool in this relation being used cooperatively with the surface U' for the determination of a diameter. In this use the blade 2 is positioned at an angle of 180° from the position of use as shown in Figures 1 and 6. As in the preceding uses the blade 2 bears against a flat end face of the object. In relation to the object the straightedge 3 is remote and the center head function is served by two outside pins 16 in the openings of the series D. The face of the head 1 adjacent the end face of the object against which the blade 2 bears is the face A and the two outside pins 16 project beyond the face A and bear against the internally presented annular surface U'. As used for the determination of a diameter one of the pins 16 (the upper pin as viewed in Figure 7) extends through the clearance opening 18, the blade 2 being held by the wing nut 11 in a position wherein its fiducial edge 10 coincides with the line which bisects the angle formed by the sides of the recess 4. As shown in Figure 7 the two outside pins 16 are fitted in openings of the series D immediately adjacent the central opening. However, if the annular surface U' be of such diameter that the two outside pins 16 thus located do not afford a sufficiently steady base, these pins may be relocated in the outer openings of the series D in which case the clearance function of the opening 18 is not required.

When the tool, as shown in Figure 1, with its straightedge bearing against the straight side of the work piece is to be used as a protractor and all of the pins 16 have their inner ends substantially flush with the face A as above described, substantially no limitation is placed upon the wide angularity or "flatness" of the plotting lines in relation to the straightedge 3, this for the reasons that the blade 2 may be pivotally moved freely across the entire extent of the face A and that the plotting lines may be drawn in either direction relatively to the center line, either by the use of the fiducial edge 10 or by use of the opposite edge 10b which is parallel to the fiducial edge. However this mode of using the tool as a protractor involves the resetting of the blade 2. If, for example, the blade 2 in the position of the tool shown in Figure 1 be positioned to extend 15° to the right of the center line, the successive positioning of the blade 2 to extend 15° to the left of the center line involves a resetting of the blade. This resetting may be avoided by securing the blade 2 by means of the wing nut 11 and by reversing the position of the tool, that is to say, changing it from the position shown in Figure 1 to the position shown in Figure 2 wherein two of the pins adjacent the straightedge 3 will project below the face A which, in the reverse position shown in Figure 2, is the lower face of the head 1.

If, however, plotting lines of extremely wide or "flat" angularity are to be drawn such as will require the positioning of the blade beyond the positions of the two pins 16 adjacent the straightedge 3 as shown in Figures 1 and 2 (wherein these pins are located in corresponding openings of an intermediate pair of the series C) the avoidance of resetting by reversal of the tool from the position which is shown in Figure 1 to the position

which is shown in Figure 2 for a use in which the pins 16 adjacent the straightedge 3 are to be used for a bearing or centering function, depends upon the relation of these pins to the blade 2. This is shown in Figure 8 wherein the blade 2 has been moved to a position in which it projects to the right of the head 1 and its fiducial edge 10 is adjacent the opening of the series E at the right. In such relation the pins 16 will be positioned in the openings of the series E and will project beyond the face A, the pin 16 in the right hand opening of the series E limiting the further movement of the blade 2 in a downward direction (as viewed in Figure 8). With the blade 2 and the pins 16 in the openings of the series E and with the wing nut 11 tightened the tool may be reversed, i. e. turned from the position of Figure 8 to the position of Figure 2, to enable the plotting lines to be drawn at the same angles but in the opposite direction while avoiding the necessity for resetting the blade. If, now, plotting lines are to be drawn beyond limits of the pins 16 in the openings of the series E these pins are shifted to the extreme openings of the series C wherein they project beyond the face A, the pin 16 in the opening at the right end of the series E (as viewed in Figure 8) being accommodated in the clearance slot 19 which will permit movement of the blade 2 to the extreme limit at which angular plotting lines may be drawn. In the manner above described the tool may be reversed, i. e. turned from the position of Figure 8 to the position of Figure 2 to enable the plotting lines to be drawn at the same angles but in the opposite direction while avoiding the necessity for resetting the blade.

Figure 9 shows the use of the tool for inscribing lines upon an inner annular surface W of a work piece X. The lines may be squaring lines or angle lines, the latter being shown. In this use of the tool the head 1 is in a plane at a right angle to the plane of the work piece X and the straightedge 3 bears against a flat face of the work piece. The blade 2 is fixed in position by the wing nut 11 and if, as shown, the tool is to be used as a protractor, angle lines may be drawn in the opposite direction by reversing the tool as above described. In these uses of the tool the piece X may be turned relatively to the tool or the tool may be turned relatively to the piece X, the blade 2 in either event following the contour of the annular surface W.

Figure 10 shows the use of the tool for inscribing lines upon the outer annular surface Y of a work piece Z. The lines may be squaring lines or angle lines, squaring lines being shown. In this use of the tool the blade 2 is shifted relatively to the head 1 to a position 180° distant from its position shown in Figure 9 and secured by the wing nut 11. As shown in Figure 10 the face B of the head 1 is outermost and the bearing of the head against a flat face of the work piece is accomplished by two of the pins 16 located symmetrically in relation to the central opening of the series D. If the tool is to be used as a protractor, the blade is set for drawing lines of appropriate angularity; and lines of corresponding angularity may be drawn in the opposite direction by reversing the tool, using two pins symmetrically located in openings of the series C for bearing purposes and inscribing the lines by means of the extension 2a. As in the use shown in Figure 9 the work piece may be turned relatively to the tool or the tool may be turned relatively to the work piece, the blade 2 in either

event following the contour of the annular surface Y.

I claim:

5 1. In a mechanic's shop work lay-out tool of the type which comprises a head having opposite flat faces and a straightedge, a blade having a fiducial edge, a pivot pin connecting the blade and the head, the blade being mounted on the pivot pin adjacent one of the flat faces of the head, being movable about the pivot pin relatively to the head in either direction to various operative positions within a range of 180° relatively to the straightedge and having its fiducial edge in radial alignment with the pivot pin, and a wing nut 10 mounted on the pivot pin for clamping the blade to the head in any position to which the blade may be moved about the pivot pin as an axis: the improvement which consists, in combination, in a first series of openings in the head adjacent and, as a series, parallel to the straightedge, the 15 openings being symmetrically arranged at opposite sides of the central point of the straightedge, a second series of openings in the head located, relatively to the straightedge, beyond the first 20 series of openings, the openings of the second series being arranged along an arc of which the pivot pin is the radial center, and a plurality of pins having uniform diameter for location selectively in the openings of the first and second 25 series and for selective cooperation with the blade or the workpiece, the pins being removable from said openings and each pin having a friction fit in any of said opening as a selected opening and for the purpose of cooperation with the blade or the work piece being manually displaceable to project from either flat face of the head with an end substantially flush with the opposite flat face of the head.

2. A mechanic's shop work lay-out tool as set forth in claim 1 wherein the head is provided on the flat face adjacent the blade with an arcuate projector scale of which the pivot pin is the radial center, the arc of the openings of the second 40 series being concentric to the projector scale, and the blade has an aligned straight extension which projects across and beyond the projector scale when the blade, in any position thereof, projects beyond the straightedge.

3. A mechanic's shop work lay-out tool as set forth in claim 1 wherein the straightedge has a 45 centrally located wide angled V-shaped recess, the openings of the first series being arranged at each side of the recess.

4. A mechanic's shop work lay-out tool as set forth in claim 1 wherein the blade is provided with an aligned straight extension beyond the pivot pin having an edge in alignment with the fiducial edge of the blade, the extension in certain 50 adjustments of the blade about the pivot pin being moved to a position in which it projects beyond the straightedge, the second series of 55 openings includes a central opening located in relation to the pivot pin along a line at right angles to the straightedge, and the extension of the blade is provided near its end and along its 60 said edge with a recess to accommodate a pin located in the central opening of the second 65 series.

5. A mechanic's shop work lay-out tool as set forth in claim 1 wherein the blade is formed with a clearance opening to accommodate a pin in an opening of the second series at one side of the center of the second series.

6. A mechanic's shop work lay-out tool as set forth in claim 1 wherein the blade has a clear-

ance slot to accommodate a pin in an extreme opening of the first series.

7. A mechanic's shop work lay-out tool as set forth in claim 1 wherein a third series of openings is provided in the head and consists of but two openings arranged along a line parallel to the straightedge, each opening of the third series being located behind and adjacent an extreme opening of the first series and serving for the accommodation of one of said pins which may be positioned to project beyond either flat face of the head.

8. A mechanic's shop work lay-out tool as set forth in claim 1 wherein a third series of openings is provided in the head and consists of but two openings arranged along a line parallel to the straightedge, each opening of the third series being located behind and adjacent an extreme opening of the first series and serving for the accommodation of one of said pins which may be positioned to project beyond either flat face of the head, and the blade has a clearance slot to accommodate a pin in an extreme opening of the first series or in an opening of the third series.

9. A mechanic's shop work lay-out tool as set forth in claim 1 wherein the blade has an aligned

straight extension which projects across the head when the blade, in any position thereof, projects beyond the straight edge.
